(57) **CLAIM**

The ornamental design for an infrared digital night vision device, as shown and described.

DESCRIPTION

FIG. 1 is a perspective view of an infrared digital night vision device showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of an indicated portion in FIG. 1. The dot-dashed broken line indicates cutoff boundaries for the enlarged view and forms no part of the claimed design. The dashed broken line portions of the infrared digital night vision device in FIGS. 1-3 represent unclaimed portions of the claimed design and form no part thereof.
